UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

TUNNEL-KILN.

1,366,369.

Specification of Letters Patent. Patented Jan. 25, 1921.

Application filed December 17, 1919. Serial No. 345,571.

To all whom it may concern:

Be it known that I, PHILIP D'H. DRESSLER, a subject of the King of Great Britain, and resident of Zanesville, in the county of Muskingum and State of Ohio, have invented certain new and useful Improvements in Tunnel-Kilns, of which the following is a specification.

My present invention comprises improvements in tunnel kilns and particularly in tunnel kilns of the well-known Dressler type. A specific object of my invention is to provide improved means for creating the necessary travel of air and products of combustion through the combustion chambers and air preheating conduits of an elongated tunnel kiln.

The general object of my present invention is to provide simple and effective means for supplying air to support combustion to a plurality of burners located in the combustion chambers at intervals along the length of the latter after preheating this air by drawing it through heat absorbing pipes in the cooling off zone of the kiln whereby the air forms a medium for abstracting heat from the goods carrier prior to their discharge from the kiln and at the same time is effectively preheated.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

Of the drawings:

Figure 1 is a somewhat diagrammatic elevation of a kiln;

Fig. 2 is a plan of a portion of the kiln in section on the line 2—2 of Fig. 3;

Fig. 3 is a transverse section on the line 3—3 of Fig. 2;

Fig. 4 is a partial transverse section on the line 4—4 of Fig. 2;

Fig. 5 is a partial transverse section on the line 5—5 of Fig. 2;

Fig. 6 is a partial section on the line 6—6 of Fig. 2;

Fig. 7 is a partial section on the line 7—7 of Fig. 6;

Fig. 8 is a partial section on the line 8—8 of Fig. 1; and

Fig. 9 is a partial section on the line 9—9 of Fig. 1.

In the drawings I have illustrated the use of my invention in a tunnel kiln of the well-known Dressler type in which the kiln chamber A proper is inclosed by the usual refractory wall B, and has lateral inlet and egress doors C and D respectively at the opposite ends of the kiln.

Adjacent the exit end of the kiln on the benches B' at the sides of the pathway B² for the goods carrying cars, are located pipes H, see Figs. 1 and 9, through which air is passed to thereby preheat the air and at the same time abstract the heat from the goods and cars as the latter move from the high temperature zone of the kiln through the cooling off zone in which the pipes H are located. The air passing through the pipes H is supplied through a tunnel I which may be open at one or both ends to the atmosphere. In line with the two sets of pipes H and extending from the latter toward the entrance end of the kiln are combustion chambers E proper. These are connected adjacent the entrance end of the kiln into pipes F, see Figs. 1 and 9, which form extensions of the combustion chambers proper. The partially cooled products of combustion pass through the pipes F to an exit tunnel G leading to a stack or other draft creating device. Air preheated by its passage through the pipes H, and combustible gas are introduced into the combustion chambers at the ends of the latter adjacent the cooling off zone of the kiln. In so far as above described in detail the apparatus shown is a typical Dressler kiln possessing nothing now novel with me.

From each of the two headers H', one at each side of the kiln to which the corresponding groups of pipes H are connected, a conduit or passage J leads downward in the masonry substructure of the kiln to a cross conduit J'. A passage JA, leading upward from the cross channel J' at the side of the kiln proper, is connected to the inlet of a fan or blower S, the outlet of which is connected by a downwardly extending passage KA to a cross passage K' formed in the masonry substructure of the kiln and connected to a tunnel K which extends longitudinally of the kiln beneath the pathway B² for the goods carrier. At intervals the tunnel K is provided with lateral branches K¹⁰ (see Fig. 4) each having at its end an

uprising extension K^{11} . Flow through each conduit K^{11} is controlled by a corresponding sliding damper M (see Figs. 6 and 7) having an operating extension M^2 which is located 5 in a tunnel or passageway M' provided for the purpose and leading to the exterior of the kiln.

The heated air rising through each passage K^{11} travels across the end of the corresponding passage M' and enters the passage L' formed in a corresponding air and gas mixing member L which may be made of cast iron or of refractory material and is embedded in the bench masonry and opens 10 at its upper end into the corresponding combustion chamber E . As shown, the member L is provided with a grid or apertured plate L^3 so that the air passing from the passage L' into the combustion chamber proper is discharged in a plurality of 15 comparatively small streams. Each member L is formed with a second passage L^2 which extends at an angle to the passage L' and communicates with the corresponding 20 gas supply passage O^{13} .

The gas supply passages O^{13} , of which there is one for each burner, each extend transversely of the kiln to the adjacent outer side of the latter and each contains 25 a sliding damper MA regulating the influx of gas into the passage O^{13} through a port O^{12} from a corresponding gas supply conduit O^{10} or O^{11} running longitudinally of the kiln. The gas supply conduit O^{10} is 30 at the right side of the kiln and the conduit O^{11} is at the left hand side of the kiln. The two gas supply conduits O^{10} and O^{11} are supplied with gas through conduit extensions O^5 and O^6 , respectively, from a 35 common gas supply pipe O . The gas supply conduits O^{10} and O^{11} are connected at their ends remote from the supply pipe O to a cross passage O^{14} with a normally closed outlet O^{15} at the exterior of the 40 kiln. The purpose of this connection is to facilitate the burning out of the conduits to remove carbon deposits and the like from time to time. In regular normal operation the cross passage O^{14} and outlet O^{15} perform no function other than that of equalizing the pressure in the two gas supply conduits O^{10} and O^{11} .

The tunnel K is provided at its end remote from the passages KA and K' with 45 lateral branches K^{20} . These have vertical extensions K^{21} which communicate with ducts K^{22} leading to the exterior of the kiln and controlled by dampers MB . The hot air leaving the kiln through the passages K^{22} may be passed directly to a stack discharging into the atmosphere or may be utilized for any purpose for which this hot air is suitable. The passages K^{20} , K^{21} and K^{22} form a convenient means for disposing 50 of air which it may be desirable to pass for

goods heating purposes through the pipes H in the cooling off zone of the kiln, in excess of the amount actually required to support combustion in the combustion chambers E under certain conditions.

As shown, each combustion chamber E is formed for the most part of tile sections formed with ventilating passages therein, such as are commonly employed in Dressler kilns, special bottom sections LE being provided at each burner into each of which the open upper end of the corresponding burner member L enters. E^{10} represents a refractory head or shield projecting over the corresponding burner member L thus preventing the air and gas entering the combustion chamber from that burner member mingling, prior to combustion, with the products of combustion introduced into the combustion chamber at a point or points 80 in the rear of that particular burner.

With the construction described the air admitted to the combustion chambers to support combustion therein, can be adequately preheated and the amount of air 90 as well as of gas supplied to each burner may be carefully regulated. It is possible, moreover, to pass through the heat absorbing pipes H of the cooling off zone all of the air which is necessary or desirable to 95 effect the desired cooling of the goods and goods carrying cars in passing through the cooling off zone, even though the air required for this purpose is in excess of that required to support combustion. An important characteristic of the apparatus shown are the provisions for obtaining the proper movements of air and gas through the various conduits and passages of the entire chamber without creating pressure 100 differentials at any one point large enough to produce appreciable leakage from the combustion chambers into the kiln chamber proper, or from the latter into the combustion chamber.

By using a stack or exhauster to create a suction at the outlet end of the combustion chambers, and a fan or blower at the opposite end of the combustion chambers, the frictional resistance to the flow of air 115 and products of combustion may be overcome with a maximum difference between the pressure in the combustion chambers and the pressure of the atmosphere only about half that which would be required 120 if the flow through the combustion chambers were wholly due to suction at one end or pressure at the other end of each combustion chamber. The special arrangement shown in which the fan or blower S 125 is placed between the air inlets to the combustion chambers and the outlets from the pipes H makes it possible to secure a desirable air pressure at the combustion chamber inlets while maintaining a pres- 130

sure in the pipes H low enough to substantially minimize leakage through the joints of those pipes.

I am about to file an application for patent on the special construction of the burner portions of the combustion chambers with the air and gas inlet provisions thereto disclosed but not specifically claimed herein.

While in accordance with the provisions 10 of the statutes I have illustrated and described the best form of my invention now known to me it will be apparent to those skilled in the art that changes may be made in the form of the apparatus disclosed herein 15 in without departing from the spirit of my invention as set forth in the appended claims and that certain features of my invention may sometimes be used to advantage without a corresponding use of other 20 features.

Having now described my invention, what I claim as new and desire to secure by Letters Patent, is:

1. In a tunnel kiln having an elongated 25 kiln chamber comprising a heating zone and a goods cooling zone at one end of the heating zone, and having an air preheating and goods cooling conduit extending along the cooling zone, and a combustion chamber 30 separated by a heat conducting wall from the kiln chamber extending along the heating zone thereof, the improvement which consists in a fan or blower having its inlet connected to the cooling zone conduit and its 35 outlet connected to the combustion chamber whereby pressure differentials tending to create leakage flow between said kiln chamber and said combustion chambers or conduit may be minimized.

2. In a tunnel kiln having an elongated 40 kiln chamber comprising a heating zone and a goods cooling zone at one end of the heating zone and having an air heating and goods cooling conduit extending along the 45 cooling zone and a combustion chamber extending along the heating zone, the improvement which consists in a fan for drawing air through said conduit and delivering a portion of said air to said combustion chamber 50 and provisions for diverting a portion of the air drawn through said conduit away from said combustion chamber.

3. In a tunnel kiln having an elongated 55 chamber comprising a heating zone and a goods cooling zone at one end of the heating zone, and having an air preheating and goods cooling chamber separated by a heat conducting wall from the kiln chamber extending along the heating zone thereof, the 60 improvement which consists in the combination of a suction device for drawing products of combustion out of the combustion chamber and a fan or blower for forcing air to support combustion through said air preheating conduit and into the combustion 65

chamber whereby pressure differentials tending to create leakage flow between said kiln chamber and said combustion chambers or conduit may be minimized.

4. In a tunnel kiln having an elongated 70 kiln chamber comprising a heating zone and a goods cooling zone at one end of the heating zone, and having an air preheating and goods cooling conduit extending along the cooling zone, and a combustion 75 chamber separated by a heat conducting wall from the kiln chamber extending along the heating zone thereof, the improvement which consists in a fan or blower having its inlet connected to the cooling zone conduit 80 and its outlet connected to the combustion chamber at the adjacent ends of said chamber and cooling zone conduit, and in combination therewith a suction device for drawing products of combustion out of the 85 combustion chamber whereby pressure differentials tending to create leakage flow between said kiln chamber and said combustion chambers or conduit may be minimized.

5. In a tunnel kiln having an elongated 90 kiln chamber with longitudinal benches therein at opposite sides of a pathway for goods carrying means and comprising a heating zone and a goods cooling zone at one end of the heating zone and having combustion 95 chambers mounted on said benches in the heating zone and air preheating and goods cooling conduits mounted on the benches in the cooling zone, the improvement which consists in a conduit system connecting said 100 goods cooling conduits to said combustion chambers comprising a portion located beneath said pathway in the heating zone with lateral outlet branches extending upward through the benches and opening to the 105 combustion chambers at intervals along the length of the latter.

6. In a tunnel kiln having an elongated 110 kiln chamber with longitudinal benches therein at opposite sides of a pathway for goods carrying means and comprising a heating zone and a goods cooling zone at one end of the heating zone and having combustion chambers mounted on said benches in the heating zone and air preheating and 115 goods cooling conduits mounted on the benches in the cooling zone, the improvement which consists in a conduit system connecting said goods cooling conduits to said combustion chambers comprising a portion 120 located beneath said pathway in the heating zone with lateral outlet branches extending upward through the benches and opening to the combustion chambers at intervals along the length of the latter, and means for separately regulating the discharge through the different outlet branches of said conduit system.

7. In a tunnel kiln having an elongated 125 kiln chamber with longitudinal benches 130

therein at opposite sides of a pathway for goods carrying means and comprising a heating zone and a goods cooling zone at one end of the heating zone and having combustion chambers mounted on said benches in the heating zone and air preheating and goods cooling conduits mounted on the benches in the cooling zone, the improvement which consists in a conduit system for 10 delivering air preheated in the cooling zone conduits to said combustion chambers at multiple points along the length of each and for supplying combustible gas to the combustion chambers at the same points, comprising a conduit located beneath the pathway for the goods having lateral outlets opening through the benches to the combustion chambers, and a pair of conduits located at the outer side of the two benches 15 and each having lateral outlets opening through the benches to the combustion chamber.

8. In a tunnel kiln having an elongated kiln chamber with longitudinal benches 25 therein at opposite sides of a pathway for goods carrying means and comprising a heating zone and a goods cooling zone at one end of the heating zone and having combustion chambers mounted on said benches 30 in the heating zone and air preheating and goods cooling conduits mounted on the benches in the cooling zone, the improvement which consists in a conduit system for delivering air preheated in the cooling zone 35 conduits to said combustion chambers at multiple points along the length of each and for supplying combustible gas to the combustion chambers at the same points, comprising a conduit located beneath the pathway for the goods having lateral outlets 40 opening through the benches to the combustion chambers, and a pair of conduits located at the outer side of the two benches, each having lateral outlets opening through 45 the benches to the combustion chamber, and means for separately regulating the discharge through each of said outlets.

9. In a tunnel kiln having an elongated

kiln chamber with longitudinal benches therein at opposite sides of a pathway for goods carrying means and comprising a heating zone and a goods cooling zone at one end of the heating zone, and having combustion chambers mounted on said benches in the heating zone and air preheating and goods cooling conduits mounted on the benches in the cooling zone, the improvement which consists in a conduit system comprising a portion located beneath said pathway in the heating zone with 55 lateral outlet branches extending upward through the benches and opening to the combustion chambers at intervals along the length of the latter and in combination therewith a fan or blower drawing air 60 through said goods cooling conduits and delivering it to said portion of said conduit system.

10. In a tunnel kiln having an elongated kiln chamber with longitudinal benches 70 therein at opposite sides of a pathway for goods carrying means and comprising a heating zone and a goods cooling zone at one end of the heating zone and having combustion chambers mounted on said 75 benches in the heating zone and air preheating and goods cooling conduits mounted on the benches in the cooling zone, the improvement which consists in a conduit system comprising a portion located beneath said 80 pathway in the heating zone with lateral outlet branches extending upward through the benches and opening to the combustion chambers at intervals along the length of the latter and in combination therewith a 85 fan or blower drawing air through said goods cooling conduits and delivering it to said portion of said conduit system, said conduit system portion having an outlet for air drawn through said cooling conduits in 90 excess of the amount required in said combustion chambers.

Signed at Zanesville, in the county of Muskingum and State of Ohio this 13th day of December A. D. 1919.

PHILIP D'H. DRESSLER.
